UNITED STATES PATENT OFFICE.

GERALD J. COUGHLIN, OF WATERTOWN, NEW YORK.

DISPLAY STAND.

1,419,616.

Specification of Letters Patent. Patented June 13, 1922.

Application filed March 6, 1922. Serial No. 541,346.

To all whom it may concern:

Be it known that I, GERALD J. COUGHLIN, a citizen of the United States, residing at Watertown, in the county of Jefferson and 5 State of New York, have invented certain new and useful Improvements in Display Stands, of which the following is a specification.

This invention relates to improvements in 10 display stands, and has for its object to provide a novel and simple device of the class adapted for mounting on the plate-glass counter shelves of meat shops, for supporting and displaying various cuts of meat and 15 other articles. A particular object is to provide display stands which may be permanently mounted at intervals in the length of the glass counter shelves, which are arranged to support detachable trays in which the 20 meats are disposed, the latter also serving to prevent any drippings of blood or grease from falling upon and fouling the plate-glass shelves. And a further object is to provide a display stand or novel, simple and 25 ornamental construction, which is strong and durable, and which may be so disposed on the shelves as not to interfere with the usual trading nor obstruct the view of goods disposed behind and beneath the glass shelves.

30 I attain these objects by the means set forth in the detailed description which follows, and illustrated by the accompanying drawing, in which—

Figure 1 is a broken side elevation of a 35 glass counter, to which a number of my display stands are applied.

Fig. 2 is an enlarged front side elevation of the complete stand.

Fig. 3 is an end elevation of the same.

40 Fig. 4 is a top-plan view of the stand, the stand being shown in dotted lines.

In the drawing, 2 represents the usual wooden base of a meat-shop counter. 3 is the upright transparent portion of the counter, upon which is mounted horizontally the plate-glass shelf 4, both of said glass parts being secured in place by brackets 5. The shelf 4 is usually held in place on the horizontal arm (not shown) of the brackets 5, 45 by means of a metal strip 6, which overlaps the adjacent ends of the sections of the shelf, and are rigidly secured to the bracket by bolts 7.

50 My display stand consists of metal, preferably, and includes a main upright standard 8, the top and bottom ends of which are

bent at right angles to provide corresponding arms 8' and 8'', the latter resting upon and being rigidly secured to the strip 6 by the bolt 7. 9 represents a similar but shorter 60 standard, which parallels the standard 8, its upper end being bent outwardly to form a horizontal arm 9', which is disposed in the same plane as the arm 8'. The lower end of the standard 9 is provided with an annular 65 foot 9'', which rests upon an angular brace 10, to which it is secured by a rivet 7''. The upper end of the brace 10 is formed into a foot 10', which engages the standard 8 and is secured thereto by a rivet 7'', while the 70 lower end of the brace 10 is provided with a horizontal foot 10'', which is secured to the strip 6 by one of the bolts 7. By constructing and arranging the several standards and brace 10, as herein shown, relatively light 75 strap metal may be employed for making the said parts, which will support heavy loads without danger of buckling or vibrating. 11 and 11' indicate similar bars which are disposed longitudinally across the corresponding 80 arm 8' and 9' of the standards, to which they are secured by bolts or rivets 7'', the said bars projecting an equal distance beyond the opposite edges of said arms. 13 and 13' are similar metal strips, which are mounted 85 transversely upon and are secured to the corresponding ends of the bars 11—11' by bolts 7''. The opposite ends of the strips 13—13' are bent upwardly to form similar alining lugs 13'', which are employed for retaining a tray or pan 15, the latter being 90 preferably loosely and detachably mounted on said strips. The tray 15 is preferably made of metal and is employed for supporting various portions or cuts of meats or 95 other articles to be displayed. The trays have a sufficient depth to safely retain the meats, and also to collect and hold any drippings from the meats, which might otherwise reach and foul the plate-glass shelves 4. 100 By providing the display stands herein shown and described, the various goods may be conveniently displayed to the customers, who may inspect them without handling, and without soiling the plate glass shelves. 105 My improved stands are so positioned on the shelves that they do not interfere with the usual trading operations, and they do not obstruct the view of the goods behind or beneath the transparent portions of the counters. The plate glass shelves referred to are 110 usually made up of several sections each

three or four feet in length, and in practice my stands are disposed at frequent intervals in the length of the counters, as shown in Fig. 1.

Having thus described my invention, what I claim as new and desire to secure by Letters Patent, is—

1. In a display stand, parallel standards of unequal length, an angular brace supporting one of the standards and rigidly secured to the other standard, parallel bars supported by said standards, and parallel strips mounted on said bars, said strips having their opposite ends bent upwardly to retain 15 a tray.

2. In a display stand, the combination with a tray, of a pair of standards disposed parallel to each other, the upper ends of said standards having similar arms disposed in 20 a common plane, a brace supporting one of

said standards and tied to the other standard, strips having their opposite ends formed into upwardly projecting lugs to receive and support the tray, and a pair of spaced bars interposed between said arms and said strips 25 and rigidly secured to both of the said parts.

3. In a display stand, the combination with a tray, of a pair of spaced strips for supporting said tray, the opposite ends of said strips provided with up-turned lugs 30 which engage the lateral edges of said tray, horizontal bars secured to the corresponding ends of said strips, a pair of standards of different lengths, each standard having an arm which is secured to one of said bars, 35 and a brace secured to the middle of one standard and supporting the other standard.

In testimony whereof I affix my signature.

GERALD J. COUGHLIN.
